UNITED STATES PATENT OFFICE.

ROBERT B. WEAVER, OF COLUMBUS, OHIO, ASSIGNEE OF ONE-HALF TO JOSEPH S. RALSTON, OF COLUMBUS, OHIO.

VALVED OUTLET MEANS FOR TANK-CARS.

1,278,813.

Specification of Letters Patent. Patented Sept. 10, 1918.

Application filed March 22, 1917. Serial No. 156,691.

To all whom it may concern:

Be it known that I, ROBERT B. WEAVER, a citizen of the United States, and a resident of Columbus, in the county of Franklin and State of Ohio, have invented certain new and useful Improvements in Valved Outlet Means for Tank-Cars; and I do hereby declare the following to be a full, clear, and exact description of the invention, such as 10 will enable others skilled in the art to which it appertains to make and use the same.

This invention relates to improvements in valved outlet means for tank cars.

Heretofore, considerable annoyance and loss have been occasioned by reason of leaky outlet valves on tank cars and on account of the manner in which such valved constructions have been applied to the tanks, access to the valves to permit their removal, 20 and regrinding as well as the regrinding of their seats has been difficult and often impossible.

One object of my present invention is to so construct valved outlet means for tank cars, that the valve and its seat may be readily removed to permit regrinding, repair or adjustment of the same.

A further object is to construct valved outlet means of the character specified, in 30 such manner as to facilitate replacement of the same in the event of breakage of the outlet tube or pipe below the valve, without necessity of removing the tank from the under-frame of the car.

With these and other objects in view, the invention consists in certain novel features of construction and combinations of parts as hereinafter set forth and pointed out in the claims.

In the accompanying drawings; Figure 1 40 is a sectional view showing an embodiment of my invention; Fig. 2 is a section on the line 2—2 of Fig. 1; and Fig. 3 is a view showing the valve operating means.

1 represents a ring having an annular 45 flange 2 and is adapted to be secured to the bottom of a tank, (a portion of which is indicated at 3,) so as to communicate with the outlet opening therein.

The ring 1 is threaded interiorly and receives the exteriorly threaded upper end of 50 a tube or pipe 4 which constitutes the discharge spout or nozzle for the tank. The tube or spout 4 is provided with an annular

flange 5 below the threaded upper end thereof and is disposed under the lower edge of the ring 1, a packing gasket 6 being disposed between the flange 5 and the lower edge of said ring 1. The ring 1 may be provided with lugs 7 which depend below the 60 flange 5 and through these lugs set screws 8 may be passed so as to engage in notches 8^a in the periphery of the flange 5.

The lower end of the tube or spout 4 may be somewhat enlarged and exteriorly threaded to receive the interiorly threaded upper portion of a reducing coupling 9, the lower contracted part of said coupling being threaded exteriorly for the reception of a cap 10. The coupling 9 may be provided 70 on its upper edge with lugs 11, through which set screws 12 pass and engage the shoulder 13 formed at the upper end of the threaded portion at the lower end of the tube or spout 4.

The discharge tube or spout 4 is beveled at its upper end to form a seat 14 for an outlet valve 15, said valve having guide wings 16 which enter said discharge tube or spout and a guide pin 16^a which passes through suitable openings in a web 15^a in said discharge tube or spout. The valve 15 may be made with a socketed shank 17 to receive a valve rod 18, the latter being secured to the socketed shank of the valve by means of a pin 85 or bolt 19. The valve rod 18 may pass upwardly through the tank and provided above the dome thereof with a cam 20 to engage a dome bracket 21 in which the upper portion of the valve stem is mounted. A crank 22 is secured to the upper end of the valve stem by means of a pin 23, for operating the valve. The valve may be maintained normally on its seat at the upper end of the valve casing or spout 4 by the action of a 90 spring 24 which encircles the valve rod and bears at its respective ends against the bracket 21 and a collar 25 secured to said stem.

The tube or spout 4 is provided with a 100 break groove 26 located just below the horizontal plane of the lower end of the winged portion of the valve. Should the tube or spout become broken, the break would occur at the groove 26, leaving the upper 105 threaded portion of said tube which provides a seat for the valve, still in place in the ring 1. This upper threaded portion of the tube

2
may be readily removed and replaced by a new tube without necessity of removing the tank from the underframe.

With my improved structure, the valve 5 and its seat are readily accessible and may be easily removed for regrinding or repair. The tube 4, which carries the seat for the valve may be readily removed by unscrewing it from the ring 1. The pin 23 which secures 10 the crank 22 to the valve stem may be removed and then said rod and the valve may be lowered sufficiently to permit access to the pin or bolt which unites the rod to the valve. Removal 15 of this bolt will then release the valve, so that the latter may be removed.

Having fully described my invention what I claim as new and desire to secure by Letters-Patent, is:

1. The combination with a tank having a discharge opening in its bottom, and a ring secured to said tank and having a depending annular flange, said ring and flange being interiorly threaded, of a discharge tube screwing into the flanged ring and forming a

valve seat at its upper end and securing 25 means carried by said annular flange and co-operating with the tube independently of its threaded portion to prevent said tube from turning.

2. The combination with a flanged ring 30 adapted for attachment to a tank at the outlet opening thereof, and a valve, of a discharge tube entering and removably secured to said ring, said tube having a seat for said valve, a flange on said tube having a notched 35 periphery and disposed under said ring, packing between said flange and ring, lugs on the ring, and screws passing through said lugs and engaging the notched periphery of 40 said flange.

In testimony whereof, I have signed this specification in the presence of two subscribing witnesses.

ROBERT R. WEAVER.
